UNITED STATES PATENT OFFICE.

WILLIAM PLEASANT JOHNSON, OF MARION JUNCTION, ALABAMA.

COMBINED BURGLAR-ALARM AND LOCK.

SPECIFICATION forming part of Letters Patent No. 789,546, dated May 9, 1905.

Application filed May 3, 1904. Serial No. 206,212.

To all whom it may concern:

Be it known that I, WILLIAM PLEASANT JOHNSON, a citizen of the United States, residing at Marion Junction, in the county of Dallas and State of Alabama, have invented a new and useful Combined Burglar-Alarm and Lock, of which the following is a specification.

My invention is an improvement in a combined burglar-alarm and lock.

The object of my invention is to provide a lock with an audible-alarm attachment in which the locking device will have a limited movement without releasing the door, window, or blind to which it is attached, said movement being sufficient, however, to release a spring-actuated alarm.

My invention consists in the novel features of construction and combination of parts hereinafter described, particularly pointed out in the claim, and shown in the accompanying drawings, in which—

Figure 1 is a perspective view showing my device applied and in locking position to a window-frame and to the window-blinds. Fig. 2 is a view of my device in locking position and applied to a door. Fig. 3 is a longitudinal section showing my device in locking position. Fig. 4 is a similar view showing limit of movement of the locking device and position first assumed by the trigger of the alarm when it has been released from said device. Fig. 5 is a section on the line 5 5 of Fig. 3.

My device comprises a metal plate A, having inwardly-bent flanges A', and this plate is adapted to be secured by screws to a window-frame casing, window-blind frame, or adjacent a door. A metal casing B, open at the top, has a bottom portion which slides on the plate A and is held to same by the flanges A'. A block B' at the forward end of the plate carries an upwardly-projecting plug B². A trigger C is pivoted adjacent the rear of the casing and carries the hammer-head C', adapted to fall upon the plug B². To the rear of the pivotal point the trigger is formed with a shoulder C². A spring B³, having a length greater than the distance between the

pivotal point of the trigger and the block B', has its forward end secured in the block and 50 its rear end secured to the trigger below the pivotal point and in advance of the shoulder. A stop-block D is arranged at the rear end of the casing, its upper surface having a shallow recess formed in it. Above the block D is pivoted a locking member D', having a notched portion D² on its undersurface, which notched portion is adapted to engage a pin E, carried by the door, window, or blind to be fastened. The locking member D' has two shoulders D³ 60 and D⁴, one on each side of the block D and adapted to contact therewith and limit the swinging movement of the locking member.

The operation of my device is as follows: The casing is slipped by hand along the base- 65 plate A until the notch D² of the locking member D' engages the pin E. The trigger C is then thrown rearward until the shoulder C² is locked under the shoulder D³ of the locking member, the shoulder D⁴ bearing on the 70 block D. If an attempt is made to raise a window or open a door or blind to which the pin E is attached, the locking member D' will be lifted by the pin, the shoulder D³ bearing on the shoulder C² and forcing the trigger 75 C into the position shown in Fig. 4, when the shoulder D³ will pass the shoulder C² and engage the block D, stopping further movement of the locking member and still retaining the notched portion D² in engagement 80 with the pin E. As soon as the shoulder C² is free from engagement with the shoulder D³ the spring B³ will draw the hammer-head C' down on the plug B², and if an explosive cap has been placed on the plug it will be exploded by the blow of the head C' and an 85 audible signal given, showing that an attempt has been made to open the door, window, or blind.

Having thus fully described my invention, 90 what I claim as new, and desire to secure by Letters Patent, is—

A device of the kind described comprising a casing, a block carried thereby having an upwardly-projecting plug, a trigger pivoted 95 in the casing and adapted to engage the plug,

2
a spring of greater length than the distance between the block and the pivotal point of the trigger secured at one end to said block and at the opposite end to the trigger, a
5 shoulder on the trigger adjacent the pivotal point, a pin carried by the window-sash, and a locking member adapted to engage the

shoulder on the trigger and the pin simultaneously and to release the trigger on limited movement of the sash.

WILLIAM PLEASANT JOHNSON.
